REFRIGERATION APPARATUS

Sidney C. Eaker and Elliott E. Grover, Springfield, Mass., assignors to Westinghouse Electric & Manufacturing Company, East Pittsburgh, Pa., a corporation of Pennsylvania

Application January 18, 1935, Serial No. 2,342

5 Claims. (Cl. 62—116)

Our invention relates to refrigeration apparatus and particularly to air cooled compression type refrigeration apparatus.

It is an object of our invention to provide improved means for circulating cooling air into and out of the machinery compartment of compression-type refrigeration apparatus, so that noise is prevented from passing out of the machinery compartment, and so that cooling air 10 circulated through the machinery compartment is not readily recirculated therethrough.

This and other objects are effected by our invention as will be apparent from the following description and claims taken in connection 15 with the accompanying drawings, forming a part of this application, in which:

Fig. 1 is a view of the back of a refrigerator cabinet embodying our improved air circulating means;

Fig. 2 is a plan view of the machinery compartment of the cabinet shown in Fig. 1, with the top of the machinery compartment removed; and

Fig. 3 is a perspective view of our improved air circulating assembly.

Referring specifically to the drawings for a detailed description of our invention, a refrigerator cabinet 11 is shown in Figs. 1 and 2 which includes a food storage compartment 12 and a 30 machinery compartment 13. The top of the machinery compartment 13 is covered by a removable cap 14 to facilitate mounting of a refrigerating unit, generally indicated at 15, in the refrigerator cabinet 11. Apertures 16 and 17 are 35 provided in a wall 18 of the machinery compartment 13 for a purpose hereinafter described.

The refrigerating unit 15 embodies a compressor 19, a motor 21 for driving the compressor and a condenser 22 wherein liquefaction 40 of compressed refrigerant vapor occurs, as is well understood in the refrigeration art. A fan 23 is also preferably disposed within the machinery compartment between the condenser 22 and motor-compressor assembly 19, 21 for forcing 45 cooling air over the motor, compressor and condenser. A shroud 20 surrounds the condenser 22 for directing the cooling air over the condenser 22.

Our improved air baffle assembly, generally 50 indicated by numeral 24, is shown in Fig. 3. The assembly includes a pan member 25 open at 26 at its lower end and provided at its upper end with a cloth connector 27. A member 28 is also attached to the upper end of the pan member 55 25 and is provided with an aperture 29 in which

a plurality of vertically-extending spaced vanes 31 of sound absorbing material are disposed. The vanes may be of any desired shape or configuration.

The baffle assembly 24 is assembled on the 5 refrigerating cabinet 11 in the following manner. The pan member 25 is fastened to the refrigerator cabinet by suitable means with the upper end thereof registering with the opening 16 in the machinery compartment 11, and with 10 the lower open end 26 below the machinery compartment 11. The cloth connector 27 is fastened to the condenser shroud 20 within the machinery compartment 11. The aperture 29 in supporting member 28 registers with the aperture 15 17 in the machinery compartment 11, and the vertically-extending spaced vanes 31 extend into the machinery compartment 13 through the aperture 17. The member 28 is also fastened to the refrigerator cabinet 11 by any suitable 20 means.

In operation, the fan 23 draws cooling air into the pan member 25 through its open end 26, the air passing through the inlet opening 16 into the machinery compartment 13. Air then is 25 drawn through the cloth connector 27, condenser shroud 20 and over the condenser 22, motor 21 and compressor 19 into the main portion of the machinery compartment 13, thus abstracting 30 heat from the apparatus in the machinery compartment. The cooling air is then forced through the passages between the spaced vanes of sound absorbing material 31 and out the exhaust opening 17 in the machinery compartment 13 and through aperture 29 in member 28 of the air 35 baffle assembly 24. The arrows shown in Fig. 2 show the direction of flow of the cooling air.

By utilizing our invention, noise from operation of the motor, compressor and fan are prevented from passing through the inlet and exhaust openings 16 and 17, respectively, in the machinery compartment 13. Noise tends to follow the direction of air flow and the vanes of sound absorbing material 31 effectively prevent 40 noises from passing through the exhaust opening 17 in the machinery compartment 13. The effect of utilizing a plurality of relatively short air passages of sound deadening material is the same as if a relatively long passage of sound 45 deadening material was utilized. Each square 50 inch of surface of the vanes 31 dampens some portion of the existing sound. By providing a large total area of sound deadening material, silencing is effectively accomplished. The cloth connector 27 and elongated pan member 25 pre- 55

vent noise from passing through the inlet opening 16 in the machinery compartment.

The arrangement also permits placing the rear of the cabinet 11 relatively close to a wall or in an alcove, without danger of immediately recirculating warm air which has been discharged from the machinery compartment 13 through the exhaust opening 17. The warm air so discharged does not reenter the exhaust opening 17 because of the restricted passages between the vanes of sound absorbing material 31, through which air is being forced outwardly, and does not reenter the inlet opening 16 because the passage 26 of the pan member 25 is disposed a substantial distance below the exhaust opening 17, the warm air, obviously, tending to rise. Prevention of recirculation insures a supply of cool air to the apparatus in the machinery compartment, whereby the refrigerating apparatus operates at high efficiency.

From the foregoing, it will be apparent that we have provided an improved construction for air cooled compression refrigeration apparatus which prevents noise from emanating from the machinery compartment housing the refrigeration apparatus, and which prevents immediate recirculation of air discharged from the machinery compartment.

While we have shown our invention in but one form, it will be obvious to those skilled in the art that it is not so limited, but is susceptible of various changes and modifications without departing from the spirit thereof, and we desire, therefore, that only such limitations shall be placed thereupon as are imposed by the prior art or as are specifically set forth in the appended claims.

What we claim is:

1. In refrigerating apparatus, the combination of a compressor, a motor for driving the compressor, walls forming a machinery compartment for housing the motor and compressor, said machinery compartment having air inlet and exhaust openings in a wall thereof, a fan for circulating air into and out of said machinery compartment through said openings, and a plurality of sound-dampening vanes disposed in spaced relation across one of said openings perpendicularly to said wall embodying said openings, said spaced sound-dampening vanes providing a plurality of substantially unrestricted passages in said last-mentioned opening from said machinery compartment and being effective to dampen the passage of noise from the machinery compartment through the last-mentioned opening.

2. In refrigerating apparatus, the combination of a compressor, a motor for driving the compressor, walls forming a machinery compartment for housing the motor and compressor, said machinery compartment having inlet and exhaust openings in one of said walls, and a plurality of sound-dampening vanes disposed in spaced relation across one of said openings perpendicularly to said wall embodying said openings, said spaced

sound-dampening vanes providing a plurality of substantially unrestricted passages in said last-mentioned opening from said machinery compartment and being effective to dampen the passage of noise from the machinery compartment through the last-mentioned opening.

3. In refrigeration apparatus, the combination of a compressor, a motor for driving the compressor, a condenser for liquefying compressed refrigerant, a shroud surrounding the condenser, a machinery compartment for housing the motor, compressor and condenser, said machinery compartment having inlet and exhaust openings therein, a fan disposed in the machinery compartment for circulating cooling air through said shroud and over the condenser, a cover pan for the inlet opening having an inlet passage at one end thereof, a cloth connector at the other end of the cover pan, said cloth connector connecting with said condenser shroud, and a plurality of sound dampening vanes disposed in spaced relation across the exhaust opening and extending into the machinery compartment, said cover pan, cloth connector and vanes dampening the passage of noise from the machinery compartment through the inlet and exhaust openings.

4. In refrigerating apparatus, the combination of a compressor, a motor for driving the compressor, walls forming a machinery compartment for housing the motor and compressor, said machinery compartment having an air outlet opening in a wall thereof and a plurality of sound deadening vanes disposed in spaced relation across said outlet opening and extending into said machinery compartment perpendicularly to the wall embodying said outlet opening, said spaced sound-deadening vanes providing a plurality of substantially unrestricted passages in said outlet opening from said machinery compartment and being effective to dampen the passage of noise from the machinery compartment through the outlet opening.

5. In refrigerating apparatus, the combination of a compressor, a motor for driving the compressor, walls forming a machinery compartment for housing the motor and compressor, said machinery compartment having an air exhaust opening in a wall thereof, a fan for directing cooling air out of the machinery compartment through said exhaust opening, and a plurality of sound-dampening vanes disposed in spaced relation across said exhaust opening and extending a substantial distance into said machinery compartment perpendicularly to said wall embodying the exhaust opening, said sound-dampening vanes providing a plurality of substantially unrestricted passages in said exhaust opening from said machinery compartment and being effective to dampen the passage of noise from the machinery compartment through the exhaust opening.
